LEE L. DODDS, OF BROOKLYN, NEW YORK.

ELECTRIC MOTOR.

1,405,502.

Specification of Letters Patent. Patented Feb. 7, 1922.

Application filed June 26, 1920. Serial No. 391,923.

To all whom it may concern:

Be it known that I, LEE L. DODDS, a citizen of the United States, residing at Brooklyn, in the county of Kings and State of New York, have invented certain new and useful Improvements in Electric Motors, of which the following is a full, clear, and exact description.

This invention relates to electric motors and particularly to types adapted to intermittent or step-by-step movements such as are employed for example, in driving secondary clocks, tickers, or small apparatus and controlled by a master mechanism. An object of my invention is to provide an improved motor which has a very short air gap in its magnetic circuit and is susceptible of a step-by-step operation, which will not overrun its increment of movement, and which will be controlled with certainty by the master mechanism.

A further object is to provide a motor of this type which is simple, compact and inexpensive, and durable, efficient, and reliable in operation. Other objects and advantages will be apparent from the following description and the novel features of my invention will be particularly pointed out in claims.

30 In the drawings:

Fig. 1 is a plan of a simple motor which has been constructed in accordance with my invention, and

Fig. 2 is a sectional elevation of the same, taken substantially along the line 2—2 of Fig. 1.

In the illustrated and preferred embodiment, I provide a bolt-shaped permanent magnet 1 for supplying a continuous magnetic field. An armature 2 having a longitudinally slotted periphery is carried by a shaft 3 which is rotatably carried by the stem 4 of the magnet 1 with the armature across the end of the stem, and rotating in a plane transverse thereto. A series of pole pieces 5 of soft iron are carried by the head plate 6 of the magnet 1 in spaced relation around the stem 4 and parallel thereto. A bearing plate 7 of brass is secured to the outer face of each pole piece 5 at the upper end thereof.

A secondary armature 8 is pivoted to each bearing plate 7 at pivot 9, the armature 8 being slightly spaced from and disposed along a side face of its pole piece but movable toward and from the same. A strip 7^a prevents direct contact of the armature 8 is different from that of the armature pro-

and its pole piece so as to eliminate danger of the armature sticking thereto. When the secondary armature has moved nearest to the pole piece, it is then preferably substantially radial with respect to the armature 2, with its inner end just clearing the projections 10 formed in the armature 2 by the slots in its periphery. A spring 11 reacts between an extension 12 of the armature 8 and brass anchor bracket 13 of the pole piece 5 to normally hold the secondary armature away from its pole piece, the secondary armature being limited in movement in this direction by any suitable adjustable stop 14. Surrounding the pole pieces 5 are electro-magnet coils 15 and 16. The electro-magnets are connected in series, parallel, or series-parallel with the line wires 17 and 18. In the illustrated embodiment the series parallel is employed for convenience, in which each electro-magnet coil 15 is connected in series with an adjacent electro-magnet coil 16. The line wires 17 and 18 are connected to a source of alternating current and I may conveniently secure such a current by connecting the wires 17 and 18 through a reversing switch 19 to direct current line wires 20 and 21, the operation of the switch producing the alternations in the direction of current flow. Any source of alternating current having the desired frequency may be employed however.

Electromagnet coils 15 are either wound or connected to the line wires so that the current therein will pass in a direction opposite from that of the other electro-magnet coil (16), whereby when all the coils are energized a magnetic field will be set up by each, the lines of force of each set of which will pass in opposite directions in alternate cores 5. Assuming that the upper end of stem 4 of the permanent magnet is a N pole, each projection 10 will have the same polarity, and the upper ends of the cores 5 would normally all be S poles. With the current passing in one direction through the line wires 17 and 18, the upper ends of the coils 15 would represent S poles due to the magnetic field set up by the passage of current in one direction through the coils, and this field would amplify that of the permanent magnet which passed through the cores 5 of these coils to produce similar polarity. Since the polarity of the upper ends of the cores of these coils is different from that of the armature pro-

jections, a strong pull between the two will take place tending to rotate the armature and bring the projections thereof which are nearest to the cores of coils 15 nearer thereto and 5 shorten the air gap. The other coils 16 simultaneously set up in their cores a magnetic field which is opposed or counter to that of the permanent magnet which normally passes through the same, so that one 10 field neutralizes or counteracts the effect of the other and no material pull between the cores of these magnets and the armature projections will take place. The armature will be rotated until the air gap between the 15 cores of coils 15 and the nearest armature projection is shortened as much as possible whereupon it will be brought to rest and held in that position. This movement brings other projections 10 adjacent to but displaced from the cores of the other coils 16. If now the direction of current in the line wires 17 and 18 is reversed by the reversing switch 19, the coils 15 will set up the opposed or counter-magnetic field and render 20 their cores ineffective upon the armature 2 and coils 16 will set up the amplifying field. This change is due to the fact that the current passes through coils 15 and 16 in opposite directions, and reversal of current 25 flow reverses the direction of their field. The upper ends of the cores of coils 16 will now have a polarity unlike that of the armature projections 10 and an attraction will occur between these cores and the nearest 30 projections. This attraction rotates the armature still further until the air gap between them is as short as it can be, and the armature will be held in this position by the attraction, and overrunning or displacement 35 will be prevented. This movement of the armature 2 under the influence of coils 16 will bring some of the projections 10 of the armature adjacent to but displaced from the upper ends of the cores of coils 15 so 40 that upon another reversal of current, the coils 15 will again become effective to amplify the permanent field and cause further rotation of the armature in the same direction. This will continue step-by-step 45 during the reversals of current flow in the line wires 17 and 18.

The operation has been described thus far as though the secondary armatures 8 were inactive, since in the broadest aspects 55 of this invention, they are in effect but extensions of the cores 5 and the motor would be operable if they were stationary. When the coils 15 amplify the permanent field, this field passes through the cores, the secondary 60 armature extensions 8 and the nearest projections 10 of the armature 2. The tendency of the lines of force is to shorten the air gaps; and thus the torque of this field will pull each active secondary armature toward 65 its pole piece and also rotate the armature

2 to bring the projections 10 which are then nearest to the active secondary armatures nearer thereto and substantially into alignment with the free ends of the latter. Overrunning of the armature 2 will be prevented 70 by this torque, and the rotary armature will thus be controlled with certainty.

The supports 7 of the secondary armatures must be of brass or similar non-magnetic material, because if iron were used the 75 lines of force would pass from the cores through the supports to the secondary armature instead of through the gap which provides the torque or pull. A similar operation occurs when the coils 16 are energized to amplify the permanent field and the coils 15 have the counter field. When the coils are connected to set up the counter or opposing field their effect upon their secondary armatures is nil and the latter will 80 be shifted away from their cores by the springs 11. A spring pawl 22 may be carried by the stationary parts and engage with the projections of the armature to prevent retrograde movement of the latter, but 85 inasmuch as I contemplate having the current constantly passing in one direction or the other, the pawl is superfluous and will not ordinarily be employed. The secondary armatures provide for a greater stroke or 90 increment of movement of the rotary armature with a much shorter air gap than would be possible without them, and the efficiency and certainty of operation of the motor is accordingly increased. If the reversals of 95 current stop, the motor will likewise stop. The period or interval between the reversals can be varied as desired, and may be accomplished by any suitable mechanism. In the illustrated embodiment I have illustrated 100 four coils, but the number can be increased or decreased as desired, or the increment of movement varied by varying the pitch of the teeth or projections of the armature and the extent of movement of the secondary armatures. 105

The effect of the opposing and amplifying fields upon the continuous field of the permanent magnet is substantially that of a field which shifts progressively in a circular 110 direction about the armature, and if the number of coils be increased with a consequently closer angular spacing the progressively shifting field effect is more marked. I have illustrated and described a permanent magnet as the source of the continuous field for polarizing the rotary armature and the T-shaped standard, but this is illustrative only of a simple embodiment, since obviously an electro-magnetic coil connected 115 to a constant source of direct current would maintain the continuous field and be in every way the equivalent of the permanent magnet. It is also obvious that various other changes in the details illustrated and de- 120 125 130

scribed may be made within the principle and scope of my invention.

I claim:

1. An electric motor comprising means for supplying a continuous magnetic field, means for progressively counteracting the effect of said continuous field at certain points and amplifying it at other points, an armature mounted at each of said points for limited pivotal movement, and a driven armature responsive to said progressive changes in the field and operable thereby toward and with the active first mentioned armature.

2. An electric motor comprising a permanent magnet, temporary magnets connected to said permanent magnet, and forming part of the external magnetic circuit of the same, an armature mounted for limited pivotal movement adjacent each temporary magnet to be operated thereby, a driven armature mounted adjacent the permanent magnet to be magnetized thereby and movable relative thereto, also toward and with the active first mentioned armatures, and means for progressively demagnetizing certain of said temporary magnets to render their corresponding armatures ineffective and additionally magnetizing other of them, the magnetic action between the additionally magnetized temporary magnets and other armatures and the driven armature producing relative movement between them.

3. An electric motor, comprising a permanent magnet for supplying a continuous magnetic field, a main armature adapted to be continuously magnetized with a certain polarity by said field, pole pieces extending from the magnet, arranged around the armature, and each having a normal polarity different from that of the armature, a secondary armature mounted for movement toward and from each pole piece, means for progressively counteracting the magnetism in certain of the pole pieces and their armatures to permit of a magnetic torque between the secondary armatures of the other pole pieces and those pole pieces and also between those secondary armatures and the main armature, and spring means normally holding the secondary armatures away from their pole pieces.

4. An electric motor comprising a rotatable armature having a series of spaced projections thereon, pole pieces adjacent the armature and disposed around the same, a secondary armature pivotally carried by each pole piece and extending in a direction radial to the armature with an end just clearing the projections of the rotary armature when against the pole piece, a spring normally holding the secondary armature slightly out of radial position, means for causing a magnetic field to pass successively through certain of the pole pieces and secondary armatures to exert a pull between the

same and projections of the rotary armature and move the effective secondary armatures toward their pole piece and also exert a torque upon the rotary armature to rotate it and bring projections substantially into alignment with the ends of the effective secondary armatures.

5. An electric motor comprising a rotary armature having spaced radial projections on its periphery, a pole piece, a secondary armature pivotally carried by said pole piece for movement toward and from the same with an end moving adjacent to but clearing the projections of the rotary armature, a spring for normally holding the secondary armature away from the pole piece, and means for intermittently causing a magnetic field to pass through the pole piece, secondary armature and the rotary armature projection then nearest to the end of secondary armature for moving the said projection adjacent to the end of the secondary armature and also both together until the secondary armature completes its stroke toward the pole piece.

6. An electric motor comprising a rotary armature having spaced radial projections on its periphery, a pole piece, a secondary armature pivoted to said pole piece for movement toward and from the same, with an end moving adjacent to but clearing the projections of the rotary armature, a spring for normally holding the secondary armature away from the pole piece, and means for normally supplying a continuous magnetic field through the pole piece, secondary armature and the rotary armature projection then nearest to the end of the secondary armature for moving the said projection until it is adjacent to the end of the secondary armature and also both together until the secondary armature completes its stroke toward the pole piece, and means for intermittently setting up a counter-magnetic field to permit of retraction of the secondary armature by the spring.

7. An electric motor comprising a rotary armature having spaced radial projections on its periphery, a pole piece, a non-magnetic support carried by the pole piece, a secondary armature pivoted to the support and slightly spaced from, but movable toward and from the pole piece, means for normally supplying a continuous magnetic field through the pole piece, secondary armature and the rotary armature projection then nearest to the end of the secondary armature for moving the said projection until it is adjacent to the end of the secondary armature and also both together until the secondary armature completes its stroke toward the pole piece and means for intermittently setting up a counter-magnetic field to permit of retraction of the secondary armature by the spring.

8. An electric motor comprising a moving main armature, having spaced projections thereon, a plurality of secondary armatures arranged along the direction of the path of movement of the projections of the main armature and mounted for limited movement in that direction, means for causing magnetic attraction between the secondary armatures and adjacent projections of the

main armature and for causing movement 10 of the same together to the extent of the said limited movement, and means for yieldingly holding the secondary armatures at the other extreme of their movement when not subjected to the said magnetic attraction. 15

In witness whereof, I hereunto subscribe my signature.
